By John S. Parker

Attorney

UNITED STATES PATENT OFFICE.

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN.

CONVEYING AND DISTRIBUTING APPARATUS.

Application filed November 30, 1920. Serial No. 427,325.

To all whom it may concern:

Be it known that I, SAMUEL SHAFER, Jr., a citizen of the United States, residing at Milwaukee, in the county of Milwaukee and 5 State of Wisconsin, have invented certain new and useful Improvements in Conveying and Distributing Apparatus, of which the following is a specification.

This invention relates to conveying and 10 distributing apparatus such as is used in paving machines for conveying concrete from the mixing machine along a boom to the place where it is to be deposited. The invention, however, is not limited to conveying and distributing mechanisms of this 15 type, being capable of application and adaptation to a wide variety of other uses.

Patents #1,267,341 and 1,290,792, to Samuel Shafer, Jr., assignor to Chain Belt 20 Company, of Milwaukee, Wisconsin, show apparatus similar in many of their features to that illustrated in the accompanying drawings, and reference is therefore made to such patents for a fuller description of the 25 details of the apparatus not herein particularly described.

Figs. 1 and 1^a together illustrate, in side elevation, an apparatus embodying my invention applied to a concrete mixer, parts 30 being broken away; Fig. 1 representing the end of the apparatus next to the concrete mixer, and Fig. 1^a the other or outer end.

Fig. 2 is a sectional view taken on the line II-II of Fig. 1.

Fig. 3 is an elevation, parts of the apparatus being in section, illustrating the mechanisms that control the movements of the doors of the conveyor bucket.

Fig. 4 is a view similar to Fig. 3, showing 40 the parts in different positions from those represented in said view.

Referring to the drawings, 2 indicates a portion of a concrete mixing machine of the rotary drum type, and 3 framework located 45 near the discharge end thereof, such framework including an upper rear extension 5 and a bracket 4. In this bracket is supported, so as to freely turn about a vertical axis, a casting 6 serving as the support for a 50 boom 8 that is united thereto by a horizontal pivot 7. This method of supporting the boom permits it to swing horizontally through a wide arc, as well as vertically, about the pivot 7. The boom is supported 55 in extended position by means of a cable 9;

passing from a winding drum 10, preferably supported on the boom, around a pulley 11 mounted in a swinging housing 12, pivotally united with the upper extension 5 of the framework; around a pulley 13 mounted on the boom near its outer end, and back to the housing 12 where its end is secured. The drum upon which one end of the cable 9 is wound may be rotated by suitable mechanism, including a hand wheel 14, so that the 60 cable serves not only to support the boom in an extended position, but also to vertically adjust it.

Mounted upon the boom so as to be free to travel from end to end thereof is a carriage or trolley 15 supporting a bucket 16 that constitutes the conveying and distributing element of the apparatus. The bucket is united with the carriage 15 by brackets 17. There are but two of these brackets, and they are preferably of angular construction so as to fit and be respectively secured to the bucket at the outer upper corners thereof. Each bracket is bifurcated at its upper end, having two arms, 18, 18', the former being connected with the carriage near its outer end, while the latter curves upwardly and inwardly and is united with the carriage near its central lower portion. This method of supporting the bucket from the carriage leaves the middle and forward portions of the bucket unobstructed by the connecting parts uniting it with the carriage so that material may be freely delivered from the 70 mixer 2 through the spout 19, without interference from such brackets and without danger that they will become covered with concrete, as would eventually be the case 75 were they in the path of the delivery of the material from the spout, or located in close proximity to that path.

Motion is imparted to the carriage to cause it to traverse the boom by means of a cable 20, supported so as to extend the full length of the boom by pulleys 21, 22, the former at the inner end of the boom, mounted in the casting 6 directly below the vertical boom pivot, and the latter at the outer end of the boom in an adjustable take-up frame 23. The cable 20 passes from the pulleys 21 upward through the hollow bearing spindle of casting 6 to pulleys 24 in the upper framework 5 and thence to a winding drum 25, to which both ends of the cable are secured, so that by turning the drum in one direction 80 85 90 95 100 105 110

the cable is moved to cause the outward traverse of the carriage and its bucket, and by turning it in the other direction, the opposite traverse of the carriage is effected. The connection between the cable and the carriage is such as to permit a limited amount of free movement of these parts relative to each other, and is preferably effected through a knock-off block 26 that is clamped to the cable. This knock-off block has grooves formed in its edges in which lie ribs or ways 27 on the inner faces of the side frame pieces of the carriage 15, and on these ways the block is free to slide to an extent limited by the stops 28 at the ends of the ways. It will be understood that when the cable 20 is moving in one direction the block slides, relatively to the carriage, along the ways 27 until arrested by one of the stops 28, after which further movement of the cable is transmitted, through the block, to the carriage which is thereby caused to move along the boom. When the motion of the cable is reversed the block travels along the ways 27 to the other end thereof where it is arrested, and thereupon motion is imparted to the carriage to move it in the opposite direction.

The cable is driven through the following train of mechanism: 29 designates the main countershaft of the concrete mixer. On this is secured a sprocket wheel 30 connected by a chain 31 with another sprocket wheel 32 free to rotate on the horizontal boom drive shaft 33. Secured to and rotating with the sprocket wheel 32 is a bevel pinion 34. The bevel pinion 34 drives two bevel gears 35 which are loose on the main boom shaft 36.

Secured fast to the bevel gears 35, being preferably integral therewith, are the driving parts of two clutches 37. The shifting elements of these clutches are secured to the shaft 36 so as to rotate therewith, but are free to be shifted laterally therewith to effect the connection of one or the other of the gears 35 with the shaft, accordingly as the clutches are adjusted. This adjustment is secured through a clutch-shifting mechanism, the details of which need not be set out, beyond stating that it has an operating handle 38 conveniently located for manipulation.

The winding drum 25 of the cable 20 is secured to the shaft 36.

It will be seen that, through the train of mechanism just described, the main boom shaft 36, and the cable drum 25, thereon, may be driven in one direction or the other from the constantly rotating power shaft 29, accordingly as the clutch shifter mechanism 38 is adjusted, and that the rotation of the shaft causes one strand or the other of the cable to be wound on the drum, the other strand being at the same time let off, and that the movements of the cable cause the

traversing of the carriage and bucket along the boom, all these movements being under the control of the operator. When the clutch shifting mechanism occupies a mid or neutral position the shaft 36 is disconnected from the source of power and the bucket traversing mechanism is at rest.

The bucket 16 is provided with bottom doors that may be locked in closing position to hold the load delivered to the bucket, and opened at will to discharge such load. The immediate means for opening, and closing and locking, the doors of the bucket are of well known construction. They include links 39 connecting the doors with a curved lock link 40, the upper end of which is pivotally united with a crank arm 41 secured to a cross shaft 42 supported in the framework of the carriage 15. These parts are so constructed as to constitute a toggle lock for holding the bucket doors closed, the pivot uniting the lock link 40 and the arm 41 being arranged to cross the axial line of the shaft 42 as the parts are moved from locking to unlocked positions. The shaft 42 is preferably provided with an operating hand lever 43 located at one side of the carriage.

Supported directly by the arm 41 is a contact roller 44, adapted to come into engagement, under conditions presently to be stated, with an adjustable stop 45 secured to the boom (see Fig. 1^a).

The boom is represented as being formed of a pair of channel irons suitably spaced apart and placed with their channels opening outwardly or away from each other, the flanges of the channel bars constituting tracks for the wheels 56 of the carriage. The stop 45 is secured to the inner face of the vertical web of one of the channel bars of the boom, in such position, relative to the top and bottom edges thereof, that it is in the path of the contact roller 44, as such roller is carried along the boom by the movements of the carriage 15, when the toggle locking devices for the doors of the bucket (which include the said crank arm 41 carrying the roller) are in locking or door-closing and holding position. When, however, the parts of the locking devices are moved to the positions they occupy when the doors are open, then the contact roller 44 is in such position that it will freely pass the stop 45 without engaging therewith. It follows, therefore, that on the outward traverse of the carriage, the doors of the bucket being closed and locked, the contact roller 44 engages with the stop 45 when that is reached, and such contact causes the door holding and locking parts to be moved to unlock the doors, whereupon the weight of the load within the bucket causes them to open and the load is permitted to be discharged. By changing the position of the stop 45, the place where the load is to be delivered can

be varied at will. On the inner traverse of the carriage, the bucket having discharged its load and its doors being open, the contact roller 44 passes the stop 45, without engagement therewith.

46 indicates a closing cam secured to the boom near its inner end. It lies between the channel bars of the boom and in position to be engaged by the contact roller 44 as the carriage approaches the inner end of its traverse. This cam is in the form of a finger depending from the boom and pointing rearwardly or toward the free end of the boom. The upper face of the finger constitutes an operating cam and along this the roller 44 rides, and by it such roller is lifted as the carriage approaches the inner end of the boom. The lifting of the roller by this cam operates to rock the crank arm 41, which in turn lifts the lock lever 40 and the links 39, and closes the doors, the parts finally being brought to their door-locking positions at about the time the carriage reaches the inner end of the boom, where it is arrested by the boom end stop 47.

Pivotedly connected with the knock-off block 26 is a latch 48. This is weighted, as at 49, so that it is normally held in a substantially horizontal position, as represented in Fig. 3, with its end or nose extending beyond the knock-off block to the rear, in which position it is locked or rigid against any horizontal force that may oppose it. From the latch extends a lug 50 in position to be engaged by the lifting cam 46, as the carriage approaches the inner limit of its movement. The end of the latch is normally in position to engage with the arm 41 adjacent to the pivot that unites it with the lock link 40 upon the knock-off block being moved toward the rear along the ways 27.

51 indicates the front boom stop with which the carriage comes into engagement as it approaches the limit of its outward traverse. This stop is yielding, being backed by spring 52 in order to lessen the shock that would occur were a rigid stop employed.

The operation of the apparatus is as follows: Supposing the parts are in the position represented in Fig. 1, that is to say, the carriage is at the rear end of the boom, where it has been arrested by the stop 47, and the knock-off block is at the rear end of the ways 27, and the bucket has been filled from the mixer through the delivery spout 19. The operator, by the proper movement of the clutch shifting lever 38, now so connects the winding drum 25 with the power shaft that the cable 20 is moved in a direction to cause the outer traverse of the carriage and bucket. At the moment this movement begins the contact roller 44 and the lug 50 are in engagement with the cam 46, having come into contact therewith as the preceding inward traverse of the carriage

toward the mixer 2 was completed. The engagement of the roller 44 with the cam operated, as has been explained, to close the doors and bring the toggle locking mechanism thereof into position to hold the doors 70

closed and locked. The engagement of the lug 50 with the cam tilted the latch 48 into the position represented in Fig. 4. By reference to this view it will be seen that when the latch occupies the position just referred to, it is out of the path of the crank arm 41, as it moved from the position it occupied when the doors were open, as represented in Fig. 3 to the door closing and locking position represented in Fig. 4, thus permitting closing of the doors without interference from the latch. The cable 20 having been started, the knock-off block 26 secured thereto slides along the ways 27 until arrested by the forward stop 28, when its motion is communicated to the carriage which travels along the boom to the place where the load within the bucket is to be discharged. This place is determined by the location of the stop 45. When this stop is 90

reached by the carriage the contact roller 44 engages therewith, and, the carriage continuing to move outward, the arm 41 is swung to the rear, releasing the doors of the bucket, which opens under the weight of 95 the load, permitting the discharge of the latter. It will be seen that the doors of the bucket are released and opened while the carriage is in motion, so that the load is more or less spread, by the continued movement 100 of the car as the discharge is taking place, as distinguished from being dumped in a heap, which takes place when the bucket is discharged while the carriage is at rest.

The bucket being thus discharged the carriage is brought to rest either by coming into engagement with the spring stop 51, or by cutting off connection of the cable 20 with the source of power before engagement with the stop takes place. It is of decided advantage in the practical operation of the apparatus to discharge and distribute the load before the outer traverse of the carriage is stopped, as the weight of the load to be arrested is thus very much lessened and shocks and strains to the apparatus are correspondingly reduced. The operator now reverses the clutch shifter and the inward traverse of the carriage begins, the knock-off block sliding, within the frame of the carriage, to its rearmost position before it communicates rearward motion to the carriage. Upon approaching the inner end of the boom the lug 50 of the latch 48, and the contact roller 44 of the crank arm 41, come successively into engagement with the cam 46, moving the latch 48 out of the way of the arm 41 and closing the doors of the bucket, as has been explained.

Should it be desired to discharge the 130

bucket before the stop 45 is reached, the direction of the cable 20 is reversed, and this causes the knock-off block to slide on its track within the carriage frame. During this sliding movement the latch 48 carried by the knock-off block engages with the arm 41 of the locking mechanism for the doors and throws it over center, whereupon the weight of the material within the bucket forces open the doors and the load is discharged.

By the arrangement shown the apparatus can be made to discharge the product of the mixer at a determined distance therefrom, by properly locating the stop 45; but should it be desirable to discharge any one or more loads of the bucket at a point or points between the mixer and that determined by the stop 45, this can be done, at the will of the operator, by means of the latch 48, as has been described.

By arranging the lifting cam, and the parts that engage therewith as described, that is, all inside the space bounded laterally by the frame pieces of the carriage, a very strong and compact mechanism is produced and one that is well protected from damage through accident, as well as from splashing concrete.

33. What I claim is:—

1. In a conveying and distributing apparatus, the combination with a track, and a discharging conveyor supported on the track, of means for causing the traverse of the conveyor backward and forward along the track, means for causing the automatic discharge of the conveyor when the desired place of discharge is reached, and means adapted to be controlled by the mechanism that causes the traverse of the conveyor, for effecting the discharge of the conveyor at the will of the operator at any desired place.

45. 2. In a conveying and distributing apparatus, the combination with a track and a conveyor supported on the track and provided with doors by which its discharge may be controlled, of means for causing the traverse of the conveyor backward and forward along the track, means for closing and locking the doors, means for causing the automatic unlocking of the doors to permit the discharge of the conveyor, when the desired place of discharge is reached, and means controlled by the mechanism that causes the traverse of the conveyor, for operating the door controlling means to permit the discharge of the conveyor at the will of the operator at any desired point, through the operation of the traversing mechanism.

55. 3. In a conveying and distributing apparatus, the combination with a track and a conveyor supported on the track and provided with doors by which its discharge

may be controlled, of means for causing the traverse of the conveyor backward and forward along the track, means for closing and locking the doors, an adjustable stop adapted to be fixed along the track at the place where the distribution of the load of the conveyor is desired and arranged to cause the automatic unlocking of the doors of the conveyor as the conveyor is moved past the stop, and means for releasing the doors to permit them to open, connected with the traversing mechanism and arranged to be brought into operation upon reversing the direction of the conveyor-traversing means from an outward to an inward movement.

4. In a conveying and distributing apparatus, the combination of a conveyor receptacle, means for causing the traverse of the receptacle back and forth along a trackway, a door that controls the discharge of the receptacle, means for holding the door closed, means controlled by the traversing means and including a contacting latch, for operating the door holding means to release the door when the traversing means are reversed from their outward to their inward movement, and means adjacent to the end of the traverse of the receptacle for moving the latch to position to permit the door to be closed and its holding means to be moved to locking position.

5. In a conveying and distributing apparatus, the combination of a carriage having side frame pieces carrying the wheels thereof, a conveyor bucket suspended therefrom, doors for controlling the discharge of the bucket, locking mechanism for holding the doors closed, including an arm pivotally supported in the carriage and located between the side frame pieces thereof and carrying a contact, means for operating the door-locking mechanism to permit a discharge of the bucket, and a cam located in a plane between the side frame pieces of the carriage and in position to engage with the contact of the said pivoted arm to move the latter to close the doors of the bucket.

6. In a conveying and distributing apparatus, the combination of a carriage, a conveyor bucket suspended therefrom, a cable for causing the traverse of the carriage back and forth along a track, a knock-off block secured to the cable through which motion is communicated from the cable to the carriage, having a limited movement relative to the carriage, doors for controlling the discharge of the bucket, a locking mechanism for holding the doors closed, including an arm pivotally supported in the carriage, a contact projection carried directly by the said arm, an adjustable stop adapted to be fixed in position to be engaged by the said contact on the outward traverse of the carriage to effect release of the bucket.

doors, and the discharge of the load, a pivoted latch carried by the knock-off block and arranged to engage with and operate the door-holding and locking mechanism for the bucket to release the doors upon motion of the traversing mechanism being reversed, and a single cam arranged to engage with the said stop to cause the closing of the bucket doors and also with the latch carried by the knock-off block to move it out of the path of the bucket closing means.

7. In a conveying and distributing apparatus, the combination of a carriage adapt-

ed to travel along an overhead track, having side frame pieces, a conveyor bucket suspended from the carriage and a pair of brackets uniting the bucket with the carriage, the brackets being connected with the bucket near its upper edge and at one end thereof and being bifurcated and diverging, the two arms being connected with the side frame pieces of the carriage, whereby the bucket is securely suspended from the carriage from one end only, leaving the other end unobstructed. 15
